PRESETTABLE COUNTER HAVING ROTARY RESETTING MEANS

This invention relates to means for locking the presetting device for presettable counters adapted to perform a rotational resetting movement.

Counting roller mechanisms are known, in which the presetting counter is preset after a hinged plate, which is normally locked by a cylinder lock, has been unlocked and opened so that the setting rollers are accessible for manual adjustment. A satisfactory presetting depends on a previous resetting of the digit wheels in the counter to a previously preset count. When the hinged plate is open, a sensing lever prevents the resetting discs from undesirably following the rotation of the digit wheels. If this rotational resetting is not prevented, a resetting to a presumably preset count after a counting operation is not possible and the presetting operation must be repeated.

This dependent of the correct counting and resetting function on the satisfactory and reliable manual control operation is improved by the present invention. The invention relates to a presetting device for presettable and rotationally resettable counters, which presetting device is locked and released by a bolt lock. The presetting device is characterized in that the presetting pushbuttons are released by an additional latch only after the resetting operation has been performed. Resetting must be performed before the pushbuttons are completely unlocked for selecting a new preset count. This arrangement ensures that the necessary resetting is performed before the selection of a new preset count.

An embodiment of the locking means for the presetting device according to the invention is functionally represented by way of example in the drawing, in which:

FIG. 1 is a diagrammatic view of the lock;

FIG. 2 is a diagrammatic view of the means for resetting the sensing lever,

FIGS. 3 and 4 are diagrammatic views showing the additional latch in both end positions; and

FIGS. 5 and 6 are a top plan view and a side elevation respectively showing diagrammatically the operation of a knob for actuating a detent lever when the digit wheels are to be reset.

Referring first to Fig. 1, there is shown a manually operable lock having a bolt 1 and cylinder 1a. The lock must be operated to release the counter for the selection of a new preset count. The rotation of the cylinder 1a disengages bolt 1 from slider link 2 so that intermediate lever 3 is disengaged from blocking lever 4. The latter prevents operation of pawls 5 which are operated by keys 6. Even when the intermediate lever has been disengaged from the blocking lever 4, the latter cannot perform a pivotal movement to its release position because it is locked by an additional latch 7, which is shown in FIG. 3. For a release of the blocking lever 4 in the arrangement according to the invention the digit wheel shaft 8 must be rotated so that the cam wheel 9 imparts to cam follower lever 10 a pivotal clockwise movement against the action of spring 11. During this pivotal movement, lever 10 cooperates with pin 12 carried by the latch 7 and imparts a pivotal counterclockwise movement to the latter against the action of a spring 13 to release the blocking lever 4. The latter now swings clockwise under the action of tension spring 14 (FIG. 4) so that the pushbutton-operated pawls 5 (FIG. 1) can engage presetting rollers 15' (FIG. 6), associated with each of which is a digit wheel 15. The rotational resetting digit wheel 15 is performed during the rotation of the digit wheel shaft 8 and before each selection of a new preset count in the arrangement according to the invention.

The intermediate lever 3 is provided with a pin 16 (FIGS. 1 and 2) which engages in an indentation 17' in the end 17" of lever 17 when lever 3 is disengaged from lever 4. This prevents the tip or end of lever 17 from being engaged in notch 18 of digit wheel 15 if this digit wheel happens to be in the zero in-

dicating position of the digit wheel. Without these locking means, the releasing device would be tripped and would then have to be reoperated by another resetting operation.

FIGS. 5 and 6 show a detent lever 19, which prevents a free movement of the digit wheel 15 when reset to a position different from its preset position. This arrangement has proved desirable because the presettable counter is not automatically returned to zero position by pinion 20. The stepping pinion only drives the digit wheel during a subsequent counting operation. Similarly, if adjacent digit wheels 15 are not set to their reset position, there will be no direct resistance to the movement of the other digit wheels 15 so that they can move freely when they have reached the incorrect position. This would result in an inaccurate positioning of the digit wheels during the subsequent counting operation.

In the present arrangement, an axially movable knob 21 (FIG. 6) is actuated to uncouple the resetting shaft 22 by moving pin 23 out of groove 23 in knob 21 when the resetting shaft 22 is in its end position. By this axial movement A, the detent lever 19 is controlled by a mechanism comprising a plunger 24, a bellcrank lever 25 and a spring 26 in such a manner that the lever 19 performs a detent action on the notched disc 15a adjacent digit wheel 15 when the resetting operation is performed and this detent action is eliminated by the axial movement of the actuating knob 21 in the direction B when the resetting shaft 22 is coupled in its end position. This is apparent from FIGS. 5 and 6 of the drawing.

What we claim is:

30 1. A rotary, presettable resetting digital counter, comprising count-storing means adapted to assume a plurality of different positions which represent different preset counts, manually operable presetting means for setting said count-storing means, rotary resetting means operable to set said count-storing means to said different positions, manually operable locking means adapted to assume a locking position in which they prevent setting of said count-storing means by said presetting means, and a latch arranged normally to lock said locking means in said locking position and to disengage said locking means when said resetting means are in a position which corresponds to the position assumed by said count-storing means, said locking means being manually operable to enable operation of said count-storing means by said presetting means only when said latch is disengaged from said locking means.

35 2. A counter as defined in claim 1, wherein said resetting means comprise a resetting shaft, a rotatable digit wheel shaft, clutch means coupling the resetting shaft to said digit wheel shaft, a cam wheel arranged to rotate with said digit wheel shaft, and a cam follower lever engaging said cam wheel and pivotally movable during rotation thereof to move said latch out of engagement with said locking means.

40 3. A counter as set forth in claim 2, which comprises spring means biasing said cam follower lever against said cam wheel and

45 4. A counter as defined in claim 2, wherein said locking means comprises a digit wheel having a zero-position indicating groove, a pivotable sensing lever having a tip arranged to fall into said groove to prevent rotation of the digit wheel, said locking means comprising a manually operable lock, an intermediate lever, and a blocking lever, said intermediate lever being engageable by said lock to lock said blocking lever in said locking position, and a pin carried by said intermediate lever and engageable by said sensing lever to keep the latter out of said groove in the digit wheel.

50 5. A counter as defined in claim 4, further comprising an actuating knob which is normally engaged with said resetting shaft and which is axially movable to uncouple said resetting shaft from said digit wheel shaft, a detent lever arranged to prevent free movement of the digit wheel when it is uncoupled from the resetting shaft, and lever means operated by said knob and arranged to deactivate the detent lever to allow free movement of the digit wheel.
